UNITED STATES PATENT OFFICE.

EMILE F. RIBBECK, OF NEW IBERIA, LOUISIANA.

CRATE.

960,401.

Specification of Letters Patent. Patented June 7, 1910.

Application filed June 21, 1909. Serial No. 503,466.

To all whom it may concern:

Be it known that I, EMILE F. RIBBECK, a citizen of the United States of America, residing at New Iberia, in the parish of Iberia 5 and State of Louisiana, have invented certain new and useful Improvements in Crates, of which the following is a specification.

This invention relates to improvements in crates, and particularly to swinging 10 crates for supporting fragile articles in such a manner as to prevent the upsetting thereof.

The object in view is the arrangement of a housing adapted to rest upon any kind of surface and a swinging support for containing merchandise positioned in the housing and arranged to remain in a substantially horizontal plane regardless of the position of the housing.

Another object of the invention is the arrangement of a crate having a frame work, either rectangular or circular, with cross pieces upon which is pivotally mounted an auxiliary housing into which is designed to be positioned merchandise of any desired 25 kind, as for instance eggs or other merchandise that is easily broken, the swinging arrangement of the secondary housing permitting the eggs or other merchandise to remain correctly in a horizontal position regardless of the position of the outer housing 30 or casing.

With these and other objects in view the invention comprises certain novel constructions, combinations and arrangement of 35 parts as will be hereinafter more fully described and claimed.

In the accompanying drawings: Figure 1 is a side elevation of an embodiment of the invention. Fig. 2 is a side elevation of a 40 slightly modified form of the invention. Fig. 3 is a detail perspective view of a secondary housing and support therefor. Fig. 4 is a longitudinal vertical section through the crate shown in Fig. 1 embodying the invention. Fig. 5 is a longitudinal vertical section through the structure shown in Fig. 2.

Referring to the drawings by numerals, 1 indicates a housing rectangular in formation provided with end cross braces 2 and 3 into which is positioned the ends of rod 4. Rod 4 is designed to support a pair of hooks 50 or links 5 and 6 which also are adapted to engage rods 7 and 8 positioned in turned-

over portions 9 and 10 of sides 11 and 12. 55 Sides 11 and 12 are made preferably from sheet metal and have the turned-over portions 9 and 10 for accommodating rods 7 and 8 whereby the same are firmly braced, and suitable means are provided for links 60 5 and 6 to engage. The turned-over portions 9 and 10 are cut away centrally thereof for accommodating links 5 and 6, as clearly shown in Fig. 3. The side plates 11 and 12 are connected by a plurality of braces 13 65 spaced any desired distance apart. The side plates 11 and 12 are also braced by having rods 14 and 15 arranged at the ends of rods 7 and 8. Rods 14 and 15 if desired may be a continuation of either of rods 7 or 8. 70

Pivots secured to rod 4 are lids 16 and 17 for protecting any merchandise that may be placed within the secondary housing formed by sides 11 and 12 and cross brace 13. By pivotally mounting lids 16 and 17 75 on rod 4 the lids are spaced somewhat above the top edge of side plates 11 and 12, and a free circulation of air is therefore provided.

In Figs. 2 and 5 a slightly modified form 80 of the invention is disclosed in which a housing 1' is provided tubular in construction. Housing 1' is braced by cross braces 2' and 3'. Positioned in cross braces 2' and 3' is the rod 4' upon which is pivotally mounted 85 an auxiliary housing 18' constructed similar to the housing shown in Fig. 3 except that it is rectangular. Housing 18' is provided with lids 16' and 17' in a similar manner to lids 16 and 17. The main difference 90 between the structure shown in Figs. 2 and 5 and the preferred structure is the construction of the outer casing for housing 1' which is tubular, and the construction of the auxiliary housing 18' which is rectangular. 95

By constructing crates having an outer housing or frame and a swinging or pivotally mounted inner housing for supporting merchandise means are presented which will prevent the easy spilling of merchandise 100 and the crushing or bruising of certain kinds of merchandise, as for instance eggs, berries and the like. By thus providing a swinging auxiliary support the outer frame or casing may be positioned on any kind of surface 105 and at any angle without in the least endangering the contents of the inner housing, provided the outer casing is not set upon

end, which in ordinary handling would not be done as the outer casing is open for free inspection.

What I claim is:-

5 In a crate, an outer casing, a rod supported centrally of said outer casing, an inner casing formed of side members, and a plurality of connecting strips, a pivotally mounted link secured to each of said side
10 members and pivotally engaging said shaft, whereby said inner casing is pivotally sup-

ported in said outer casing, and a plurality of pivotally mounted members connected to said shaft for forming a lid for said inner casing.

15

In testimony whereof I affix my signature in presence of two witnesses.

EMILE F. RIBBECK.
